(57) **CLAIM**

The ornamental design for a front bezel for computer enclosure, as shown and described.

DESCRIPTION

FIG. 1 is a perspective view of a front bezel being mounted to a computer enclosure showing our new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof in the open position for explanatory purpose only and in a reduced scale.

Broken lines are for illustrative purposes only and form no part of the claimed design.
